US00D877198S

(12) **United States Design Patent** (10) Patent No.: **US D877,198 S**
Lee et al. (45) Date of Patent: ** Mar. 3, 2020

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Heon Woo Lee**, Seoul (KR); **Miyeon Park**, Seongnam-si (KR); **Yongman Park**, Yongin-si (KR); **Jakyung Lee**, Seoul (KR); **Hyerim Kwak**, Seoul (KR); **Soyoung Lee**, Seoul (KR)

(73) Assignee: **SAMSUNG ELECTRONICS CO., LTD.**, Suwon-si (KR)

(**) Term: **15 Years**

(21) Appl. No.: **29/704,486**

(22) Filed: **Sep. 5, 2019**

Related U.S. Application Data

(62) Division of application No. 29/685,648, filed on Mar. 29, 2019, now Pat. No. Des. 862,521, which is a division of application No. 29/658,894, filed on Aug. 3, 2018, now Pat. No. Des. 848,481, which is a division of application No. 29/610,568, filed on Jul. 13, 2017, now Pat. No. Des. 826,987, which is a division of application No. 29/564,978, filed on May 17, 2016, now Pat. No. Des. 796,528.

CLAIM

The ornamental design for a display screen or portion thereof with graphical user interface, as shown and described.

DESCRIPTION

The FIGURE is a front view of a display screen or portion thereof with graphical user interface showing our new design.

The broken lines at the outer perimeter of the FIGURE depict a display screen or portion thereof and form no part of the claimed design. The remaining broken lines in the FIGURE depict portions of the graphical user interface that form no part of the claimed design.
